(57) **CLAIM**

The ornamental design for a point-of-sale terminal mounting adapter, as shown and described.

DESCRIPTION

FIG. 1 is an isometric view of one embodiment of the present invention with the environment shown in broken lines forming no part of the claim;

FIG. 2 is a side elevation view of the embodiment of the invention shown in FIG. 1 with the environment shown in broken lines forming no part of the claim;

FIG. 3 is a second side elevation view of the embodiment of the invention shown in FIG. 1 with the environment shown in broken lines forming no part of the claim;

FIG. 4 is a topside plan view of the embodiment of the invention shown in FIG. 1 with the environment shown in broken lines forming no part of the claim;

FIG. 5 is a bottom-side plan view of the embodiment of the invention shown in FIG. 1 with the environment shown in broken lines forming no part of the claim;

FIG. 6 is an end elevation view of the embodiment of the invention shown in FIG. 1 with the environment shown in broken lines forming no part of the claim;

FIG. 7 is another end elevation view of the embodiment of the invention shown in FIG. 1 with the environment shown in broken lines forming no part of the claim;

FIG. 8 is an isometric view of another embodiment of the present invention;

FIG. 9 is a side elevation view of the second embodiment of the invention shown in FIG. 8;

FIG. 10 is a second side elevation view of the second embodiment of the invention shown in FIG. 8;

FIG. 11 is a topside plan view of the second embodiment of the invention shown in FIG. 8;

FIG. 12 is a bottom-side plan view of the second embodiment of the invention shown in FIG. 8;

FIG. 13 is an end elevation view of the second embodiment of the invention shown in FIG. 8; and,

FIG. 14 is another end elevation view of the second embodiment of the invention shown in FIG. 8.
